LOCOMOTIVE STOKER

Charles J. Surdy, Erie, Pa., assignor to The Standard Stoker, Incorporated, a corporation of Delaware

Application August 18, 1939, Serial No. 290,832

6 Claims. (Cl. 110—105.5)

This invention, which relates to locomotive stokers, has for its principal object the provision of a stoker which may be cheaply applied to existing forms of locomotive boilers without material change in the structure thereof.

It is also an object of this invention to provide a locomotive stoker which feeds fuel through the existing firing opening in the backwall of the locomotive boiler, the coal passing freely through such opening and dropping downwardly into the firebox along the backwall to form a pile or mound from which it is distributed over the grates by means of a pressure fluid jet.

It is a further object of this invention to so position the distributor jet in stokers of the characters above described that a low firebed may be maintained upon the firebox grates.

It is also an object of this invention to arrange the pressure fluid jet for adjustment in a vertical and horizontal direction in order to control distribution of coal over the firebed.

These and other objects together with their attendant advantages will become apparent as the following description is read in connection with the accompanying drawings, in which

Fig. 1 is a central vertical section through the rearward part of the locomotive boiler showing the stoker of the present invention in similar section with parts thereof in side elevation;

Fig. 2 is a section in plan taken along the lines 2—2 of Fig. 1;

Fig. 3 is an enlargement of a portion of Fig. 1 showing in greater detail the pressure fluid jet head as applied to the locomotive boiler; and

Fig. 4 is a view from within the firebox of the structure shown in Fig. 3.

Referring now to these drawings, the locomotive L comprises a boiler 10 having a firebox 11 which is defined by the backwall 12, the front wall 13, and side walls 14 and 15. These walls are hollow for the purpose of circulating water as it is evaporated by the boiler 10. The bottom of the firebox 11 is formed by the main grates 16 which are arranged for rocking movement through the intermediacy of the levers 17, and the dump grate 9 at the rearward portion of the firebox arranged for downward movement about the pin 8 by means of the link 7. Extending centrally of the locomotive, with its upper surface in the plane of the grate 16 is a grate bearing bar 6, the rearward end 5 of which is enlarged, for the purpose to be hereinafter explained. One dump grate 9 is disposed at each side of the enlarged rearward end 5 of the grate bearing bar 6.

Below the locomotive boiler 10 is a frame 18 upon which the boiler is supported by means including the flexible plates 19 and 20. An ash pan 21 extends downwardly below the grates 16 and receives the ash which falls through the openings in the grates 16 while the locomotive is in operation and also whenever the grates are rocked by the levers 17. In order to promote combustion, the firebox 11 is provided with the usual arch 22 formed of refractory material which serves as a baffle for the flame and products of combustion in their travel toward the flues 23. A cab 24 extends rearwardly from the backwall 12 and is provided with a floor 25 spaced above the frame 18 but below the level of the firing opening 26, the latter being formed in the backwall 12 at a suitable height above the level of the grates 16.

In applying stokers to locomotives of the type herein described, it is important to do so with a minimum alteration in the structure of the latter so that low installation costs may be maintained. Since the firing opening 26 is often times just of sufficient size to permit mechanics to enter therethrough for making periodical inspections of the firebox and for making repairs thereto, the application of a stoker with its distributing mechanism passing through such opening is not usually feasible but requires an enlargement of this opening. In the present invention, the stoker S, while being adapted to feed fuel through opening 26, does not occupy a substantial portion of the firing opening 26 because the distributing mechanism is positioned independently as will hereinafter appear.

The stoker S includes a conveyor conduit 30 leading forwardly from the tender and universally connected at 31 to the lower end of an inclined conveyor conduit 32 which is rigidly secured by bolts to the bracket 33 carried upon the locomotive backwall 12. A conveyor screw 34 within the conduit 32 urges fuel therethrough and through the lower portion 35 of a casing 36 which embraces the firing opening 26 and is provided opposite such opening with an aperture 37 adapted to be closed by a power operated fire-door 38. A guard plate 39 extends forwardly from the lower portion of the casing 36 into the firing opening 26 and over which guard plate fuel is urged forwardly by the screw 34. In order that there may be no substantial obstruction of the firing opening 26, the guard plate 39 fits closely to the walls which define the firing opening.

At a substantial distance below the lower edge

of the firing opening 26 and approximately in the plane of cab deck 25 the backwall 12 has inserted therethrough a tube or thimble 40 through which extends a pressure fluid jet head 50. The jet head 50 receives fluid under pressure from pipes 51 which lead from a suitable source of supply and discharges the pressure fluid forwardly and laterally through apertures 52 formed in its arcuate front face 53.

The forward portion 55 with which the arcuate front face 53 of the jet head is formed is provided on its upper side with a gable formation 56 so related with the spill edge 57 of the guard plate 39 that as fuel drops by gravity from the latter it will strike the gable 56 and roll downwardly without resting upon any part of the jet head. This will materially increase the life of this jet head 50 since no fuel will be permitted to lodge and ignite thereupon. Rearwardly of its front portion 55 the jet head 50 is provided with a shank 58 terminating exteriorly of the firebox backwall 12 in a spherical ball 59 arranged to be received in a complementary spherical seat 60 of a support bracket 61 secured by bolts to the backwall 12. The spherical ball 59 is provided on its top and bottom with an arcuate groove 62 extending in a vertical longitudinal plane passed through the axis of the ball. Screws such as 63 threaded into the spherical seat 60 engage a respective arcuate groove 62 for securing said jet head 50 in any position of adjustment vertically and horizontally to a degree limited by the size of the thimble 40.

In the operation of this device, and with a thin, level fire in the firebox 11 already started by round-house forces, the screw 34 of the stoker delivers fuel through the lower portion 35 of the casing 36 and across the guard plate 39, from the spill edge 57 of which the fuel will drop downwardly somewhat after the fashion of a waterfall. The falling fuel will strike the gable 56 of the jet head 50 and within a short time will build up a pile or mound of fuel under the jet head to the level of the pressure fluid discharge apertures 52. As the fuel continues to fall onto the mound of fuel so formed, it is swept off this mound in a forward and lateral direction by the pressure fluid blasts issuing from the jet apertures 52 and deposited upon the thin fire burning on the grates 16. In order to insure the maintenance of a thin firebed, the jet head 50 is so positioned that the vertical distance from the grates 16 to the jet apertures 52 is less than the vertical distance from these jet apertures to the lower edge of the firing opening 26. In time the level of the fire will build up to a level indicated by the dot and dash lines in Fig. 1, which is a level at which the boiler 10 may evaporate the maximum quantity of water hourly. Should it be found that the firebed is building up in front of the jet apertures 52, the grate sections 16 may be shaken lightly to remove the ash at the bottom of the firebed, causing it to settle downwardly. A heavier bed of fire can be carried, if desired, by tilting upwardly the jet head 50 about the axis of the spherical ball 59. This will cause the jet apertures to issue upwardly inclined jets of pressure fluid and give greater trajectory to the fuel. It will, of course, be understood that since that portion of the fuel immediately beneath the jet head 50 is not replenished, it will soon burn away and become ash so that there is no hot flame impinging upon the forward portion 55 of the jet head 50. The enlarged rearward portion 5 of the grate bearing bar 6

serves to retain a bed of ash beneath the front portion 55 of the jet head 50 since movement of the grate section 16 or dump grates will not disturb ash formation at this point.

From the foregoing description it will be apparent to those familiar with the art that a stoker constructed according to the present invention is readily applied to existing locomotives and insures maintenance of a low firebed necessary for maximum boiler efficiency.

I claim:

1. In a locomotive firebox, a hollow backwall provided with a firing opening therein and grates forming the bottom of said firebox disposed below the lower marginal edge of said opening, a stoker conveyor adapted to feed fuel through said firing opening into said firebox so as to form a mound of fuel on said grate at the rearward portion of said firebox beneath said firing opening, means providing a passage through said hollow backwall beneath said firing opening, a pressure fluid jet head extending through said passage having a front face disposed within the rearward portion of said firebox beneath said firing opening and above the level of said grates, said grates constituting the sole means for supporting the fuel dropping from said firing opening, the front face of said jet head being provided with a plurality of jet apertures directed forwardly and laterally across said firebox, and means for supplying fluid under pressure to said jet head for issuance from said jet apertures for projecting fuel from the mound of fuel on said grate to all parts of the firebox, the vertical distance from the level of said grates to said jet apertures being less than the vertical distance from said jet apertures to the lower marginal edge of said firing opening.

2. In a locomotive firebox, a hollow backwall provided with a firing opening therein and grates forming the bottom of said firebox disposed below the lower marginal edge of said opening, a stoker conveyor adapted to feed fuel through said firing opening into said firebox so as to form a mound of fuel on said grate at the rearward portion of said firebox beneath said firing opening, means providing a passage through said hollow backwall beneath said firing opening, a pressure fluid jet head extending through said passage having a front face disposed within the rearward portion of said firebox beneath said firing opening and above the level of said grates, said grates constituting the sole means for supporting the fuel dropping from said firing opening, the front face of said jet head being provided with a plurality of jet apertures directed forwardly and laterally across said firebox, means for supplying fluid under pressure to said jet head for issuance from said jet apertures for projecting fuel from the mound of fuel on said grate to all parts of the firebox, the vertical distance from the level of said grates to said jet apertures normally being less than the vertical distance from said jet apertures to the lower marginal edge of said firing opening.

3. In a locomotive firebox, a hollow backwall provided with a firing opening therein and grates forming the bottom of said firebox disposed below the lower marginal edge of said opening, a stoker conveyor adapted to feed fuel through said firing opening into said firebox so as to form a mound of fuel on said grate at the rearward portion of said firebox beneath said firing open-

ing, means providing a passage through said hollow backwall beneath said firing opening, a pressure fluid jet head extending through said passage having a front face disposed within the rearward portion of said firebox beneath said firing opening and above the level of said grates, said grates constituting the sole means for supporting the fuel dropping from said firing opening, the front face of said jet head being provided with a plurality of jet apertures directed forwardly and laterally across said firebox, means for supplying fluid under pressure to said jet head for issuance from said jet apertures for projecting fuel from the mound of fuel on said grate to all parts of the firebox and means for adjusting the position of said jet head in a lateral direction with respect to said firebox, the vertical distance from the level of said grates to said jet apertures being less than the vertical distance from said apertures to the lower marginal edge of said firing opening.

4. In a locomotive firebox, a hollow backwall provided with a firing opening therein and grates forming the bottom of said firebox disposed below the lower marginal end of said opening, a stoker conveyor adapted to feed fuel through said firing opening into said firebox so as to form a mound of fuel on said grate at the rearward portion of said firebox beneath said firing opening, a pressure fluid jet provided with a front face disposed within the rearward portion of said firebox beneath said firing opening and above the level of said grates, said grates constituting the sole means for supporting the fuel dropping from said firing opening, the front face of said jet head being provided with a plurality of jet apertures directed forwardly and laterally across said firebox, and means for supplying fluid under pressure to said jet head for issuance from said jet apertures for projecting fuel from the mound of fuel on said grate to all parts of the firebox, the vertical distance from the level of said grates to said jet apertures being less than the vertical distance from said jet apertures to the lower marginal edge of said firing opening.

5. In a locomotive firebox, a hollow backwall provided with a firing opening therein and grates forming the bottom of said firebox disposed below the lower marginal end of said opening, a stoker conveyor adapted to feed fuel through said firing opening into said firebox so as to form a mound of fuel on said grate at the rearward portion of said firebox beneath said firing opening, a pressure fluid jet provided with a front face disposed within the rearward portion of said firebox beneath said firing opening and above the level of said grates, said grates constituting the sole means for supporting the fuel dropping from said firing opening, the front face of said jet head being provided with a plurality of jet apertures directed forwardly and laterally across said firebox, and means for supplying fluid under pressure to said jet head for issuance from said jet apertures for projecting fuel from the mound of fuel formed on said grate to all parts of the firebox.

6. In a locomotive firebox, a hollow backwall provided with a firing opening therein and grates forming the bottom of said firebox disposed below the lower marginal edge of said opening, a stoker conveyor adapted to feed fuel through said firing opening into said firebox so as to form a mound of fuel on said grate at the rearward portion of said firebox beneath said firing opening, means providing a passage through said hollow backwall beneath said firing opening, a pressure fluid jet head extending through said passage having a front face disposed within the rearward portion of said firebox beneath said firing opening and above the level of said grates, said grates constituting the sole means for supporting the fuel dropping from said firing opening, the front face of said jet head being provided with a plurality of jet apertures directed forwardly and laterally across said firebox, and means for supplying fluid under pressure to said jet head for issuance from said jet apertures for projecting fuel from the mound of fuel formed on said grate to all parts of the firebox.

CHARLES J. SURDY.
